G. H. Aylworth
Inventor.

UNITED STATES PATENT OFFICE.

GEORGE H. AYLWORTH, OF BRIGHTON, ILLINOIS.

SASH-FASTENER.

SPECIFICATION forming part of Letters Patent No. 396,320, dated January 15, 1889.

Application filed July 20, 1888. Serial No. 280,551. (No model.)

To all whom it may concern:

Be it known that I, GEORGE H. AYLWORTH, a citizen of the United States, residing at Brighton, in the county of Macoupin and State of Illinois, have invented certain new and useful Improvements in Sash-Locks; and I do hereby declare the following to be a full, clear, and exact description of the invention, such as will enable others skilled in the art to which it appertains to make and use the same.

The object of my invention is to provide a sash-lock which shall be cheap, simple in construction, and reliable and effective in operation.

15 To these ends the invention consists in a suitable case or box provided with a guide groove or slot in its bottom, and curved circularly-movable locking-bolt within the case, and having its inner end guided and controlled by the guide-slot in the bottom.

20 In the accompanying drawings, which illustrate my invention and form a part of this specification, Figure 1 is a face or top view with the top or cover of the case removed and the locking-bolt in retracted position, as when the sash is unlocked. Fig. 2 is a similar view showing the bolt projected, as when the sash is locked.

25 A designates the case, which is preferably rectangular in shape, though it may be made in any other preferred form, and a the surrounding rim, which is cut away at a' to form an opening, through which the bolt is projected in locking.

30 a^2 designates a curved slot in the bottom of the case, the curvature of said slot preferably coinciding with the curvature of the bolt.

35 B designates the locking-bolt, which is curved, as shown in the drawings. On its inner side, at a distance from its locking end, is a shoulder, b , which comes in contact with a stop, a^3 , within the case at one side of the opening through which the bolt is projected, and by which the locking movement of the bolt is limited. The inner end of the bolt has a stud or pin projecting from its under side, which pin projects into the groove or slot a^2 to guide and control the movement of this end of the bolt, the opposite or locking

end being controlled by the opening in the case through which it is projected.

50 C designates a spring, which may be of any preferred form and applied in any suitable manner, to project the bolt. As shown in the drawings, it is formed of spring-wire bent or coiled at the center to form a loop, c , which is placed over a pin or stud, a^4 , rising from the bottom of the case, one end of the spring bearing against the side of the case and the other against a pin or shoulder on the bolt. 60

At the end of the case, below the opening for the bolt, is a hollowed seat, a^5 , in which the end of the bolt rests when in its retracted position. The action of the spring C being in the direction of a line between its bearing-point on the bolt and the seat a^5 , the bolt will be held in retracted position till its locking end is thrown forward upon the outwardly-inclined portion a^6 of the seat, when the curvature of the bolt will permit the spring 70 to throw it easily forward.

While I prefer to give the slot a^2 the same curvature—*i. e.*, the same radius—as the bolt, and to describe it from a point which shall bring it and the opening in the case through which the bolt is projected into the same circle, it may have a greater or less radius and may be described from a different center. By changing the radius of the slot or its angle with respect to the opening through which 80 the bolt is projected, so as to bring the two ends of the bolt into circles of different radius or into circles of the same radius described from different centers, the locking end of the bolt may be made to stand higher or lower 85 when projected, and may thus be caused to act as a lever to hold the sash up or down to prevent rattling. The bolt is provided with the usual button or handle for operating it, which handle projects through a slot in the 90 cover (not shown) of the case.

While I have shown a spring for projecting the bolt, I desire to state that this is not an essential part of my invention, and may be omitted if preferred, leaving the bolt to act 95 by gravity.

Having now described my invention, I claim—

1. In a sash-lock, the combination of a case having in its bottom a curved guide slot or groove, and a curved bolt having at its inner end a pin which projects into said guide-slot and governs the movement of the inner end of the bolt when the latter is projected.

2. In a sash-lock, the combination, with the case having in its bottom a curved guide slot or groove, of a curved bolt, B, having at

its inner end a pin which projects into said guide-slot, and a spring, C, for projecting the bolt, substantially as shown and described.

In testimony whereof I affix my signature in presence of two witnesses.

GEORGE H. AYLWORTH.
